DESIGN FOR A RUNNING BOARD COVER

Claude W. Beardsley, San Diego, Calif.

Application May 25, 1936, Serial No. 62,833

Term of patent 14 years

To all whom it may concern:

Be it known that I, Claude Wm. Beardsley, a citizen of the United States, residing at San Diego, in the county of San Diego and State of California, have invented a new, original, and ornamental Design for a Running Board Cover, of which the following is a specification, reference being had to the accompanying drawing, forming part thereof.

Fig. 1 is a perspective view of a running board cover showing my new design.

Fig. 2 is a section taken on line 2—2 of Fig. 1 in the direction in which the arrows point, a part of the device distantly seen beyond the line of section appearing also in the figure.

I claim:

The ornamental design for a running board cover substantially as shown.

CLAUDE WM. BEARDSLEY.
